CLAIM

We claim the ornamental design for shotgun wad, as shown and described.

DESCRIPTION

FIG. 1 is a perspective view of a shotgun shell wad according to the invention. The view from the opposite side being identical thereto.

FIG. 2 is a perspective view of the shotgun shell wad of FIG. 1 with the fins in a deployed flared position after firing. The view from the opposite side being identical thereto.

FIG. 3 is an elevational view of the shotgun shell wad of FIG. 1. The view from the opposite side being identical thereto.

FIG. 4 is a perspective view of the shotgun shell wad of FIG. 1 with the fins in a deployed flared position after firing. The view from the opposite side being identical thereto.

FIG. 5 is a top end view of the shotgun shell wad of FIG. 1; and,

FIG. 6 is a bottom end view of the shotgun shell wad of FIG. 1.

The portions of the shotgun wad shown in broken lines form no part of the claimed invention.
